QUICK DETACHABLE COUPLING

Carl A. Weise, Los Angeles, Calif., assignor to
 Douglas Aircraft Company, Inc., Santa Monica,
 Calif.

Application February 6, 1946, Serial No. 645,721

9 Claims. (Cl. 285—129)

1

This invention relates to couplings and more particularly to the type of coupling adapted to secure abutting flanged pipe or conduit members against relative movement.

The invention comprises a plurality of arcuate clamping members which are adapted to girdle the jointure of two or more abutting flanged pipe members, and retain them in locked engagement by suitably positioned quick acting clamping bands.

Each of the arcuate clamping members is provided with an inwardly disposed groove or bight portion adapted to encompass the abutting flanges of the pipes. The bight portion of the clamping member flares outwardly at the base portion thereof to provide coniform flanges which are disposed one on either side of the pipe jointure. A pressure plate is disposed between and secured to the extremities of the coniform flanges to form a bridge, thus providing a clamping member which is substantially triangular in cross-section. Grooves are provided along the outer surface of the pressure plate adjacent to the edges of the same which are adapted to receive the quick acting clamping bands. These bands, when in place, exert pressure against the coniform flanges which in turn push inwardly to squeeze the inner cam face portions of the bight together and resiliently grip the flanges of the abutting pipes to prevent relative movement of the same.

In certain applications of the invention where it is necessary to provide a gas tight joint, an asbestos packing can be inserted in the groove of the clamping member bight. Tightening of the clamping bands against the pressure plate forces the bight inwardly against the flanges of the pipe jointure so that the asbestos packing, positioned in the bight, is brought into pressural engagement with the edges of the flange to seal the same against leakage of gas or fluid.

This coupling operation is performed wholly on the outside of the flanged members to form a sealed, gas tight jointure which can be quickly and easily disconnected at any time without changing the spacing of the joints or altering the structure at the end of the pipe. If, for instance, the packing should develop a leak, the clamp may be removed and new packing inserted without moving either of the pipe sections laterally or longitudinally.

The various features of the flanged joint forming the subject of the present invention are illustrated in a preferred form in the accompanying drawings in which:

2

Figure 1 is a perspective view of the quick detachable coupling as applied to a pair of pipe ends to be joined;

Figure 2 is a cross-sectional view of the coupling taken along line 2—2 of Figure 1;

Figure 3 is a side elevational view of the quick acting clamp forming a part of the coupling; and

Figure 4 is an enlarged fragmentary top view of the pressure plate which encircles the pipe flanges.

The coupling illustrated in Figure 1 of the drawing comprises a plurality of clamping members, each of which is formed as an arcuate strip of material 11 having a bight portion forming an inwardly disposed re-entrant groove 12. The width of the groove formed by the bight is equal to the combined thickness of the flanges to be joined, and the adjacent faces 13 and 14 of the bight are adapted to engage the outwardly disposed flange faces 15 and 16 of the flanged pipe members 17 and 18. The base portion of the bight flares outwardly to provide conically extending flanges 20 and 21 which are disposed one on either side of the flanged jointure.

An arcuate pressure plate 23 is welded or otherwise secured at a plurality of spaced points 24 and 25 to the free edges of the flanges 20 and 21 to form a bridge therebetween and provide a clamping member having a substantially triangular cross-section as shown in Figure 2. Grooves 26 and 27 are provided along the edges of the plate 23 by reversing the curvature of the material and are adapted to receive quick acting clamps 28, one in each groove.

The clamp 28 in the present invention comprises an arcuate rod 29, one end of which is anchored at 30 to an anchor block 31. A hasp 32 is pivotally attached at 33 to a terminal member 34, which in turn is threaded at 35 to the opposite end of the rod 29. As shown in Figure 3 of the drawing, the hasp 32 is provided with a node 36 which engages a groove 37 in the anchor block 31, to draw the rod in tension around the joint. The relationship between the anchored end 30 of the rod 29 and the pivoted joint of the hasp 32 is such that an off center linkage is provided. This off center linkage tends to retain the clamp in the locked position on the pressure plate of the clamping members. The threads 35 are provided on the end of the rod 29 so that the length of the same girdling the pipe can be adjusted according to the pressure desired against the joint to make it gas tight.

When the pipes 17 and 18 are brought into engagement so that the flanges abut one another,

the sections of the clamping member may then be assembled in place around the jointure. Where it is desirable to provide a gas tight pipe joint, an asbestos compound packing 22 or other suitable packing material can be inserted in the bight so that the same will rest against the edges of the pipe flanges and seal them against leakage of gas or fluid. The rods 29 forming a part of the quick acting clamp are then arranged in the grooves 26 and 27 provided therefor in the pressure plate. The node 36 of each hasp 32 is brought into engagement with the groove 37 in the anchor block. The hasps 32 of both quick acting clamps are then pressed inwardly toward the joint so that the full length of the rods 29 are brought into pressural engagement with the grooves 26 and 27 along the edge of the pressure plate 23, and are made safe with wire or any other suitable means of fastening.

Simultaneously with the closing of the hasps 32, radial pressure is exerted against the clamping member pressure plates 23 by the squeezing action of the rods 29. The faces 13 and 14 of the members slide inwardly on flanges 15 and 16 as the diameter of the clamp decreases. However, when the packing 22, positioned in the bight 12, makes pressural engagement with the edge of the abutted flanges of the pipes 17 and 18, inward movement of the clamping members is arrested.

This arrest of inward movement causes the bend or base portion of the bight to become a pivot point for movement of the pressure faces 13 and 14 toward each other and against the flange faces 15 and 16 resulting from the radial pressure of rods 29. This gripping action squeezes the flanges together so that the pipes 17 and 18 cannot be relatively moved.

Since the tightening of rods 29 requires a decrease in the perimeters of the edges of clamping members 10 they are provided with notches 38, allowing relative movement of the sections. It is desirable, in the use of the present invention in aircraft applications, to keep the coupling as light as possible. Accordingly, as shown in Figure 4 of the drawings, the notches 38 may be made triangular in shape, producing a substantial reduction in weight without sacrificing the strength of the joint.

It will be apparent to those skilled in the art that various changes and modifications may be made in the coupling hereinabove described without departing from the spirit of the invention and it is intended to encompass all such changes and modifications within the scope of the following claims.

I claim:

1. A jointure, comprising: a plurality of couplable members; a plurality of arcuate members surrounding the members to be coupled, each arcuate member having a transversely-extending resiliency adapted to embrace the members to be coupled; means surrounding said arcuate members laterally of said resiliency and adapted to be diametrically constricted; and means operatively interposed between the last-said means and said resiliency for effecting reduction in the transverse dimension of said resiliency, whereby to longitudinally apply immobilizing compressive forces to said couplable members.

2. A jointure, comprising: a pair of abutted members; longitudinally spaced surfaces extending transversely of the joint and resiliently integrated at their outer ends to embrace at least portions of the abutted members; a lateral extension of the inner end of each of said transversely

extending surfaces; a member extending from the outer end of each of the lateral extensions to the outer portion of the transverse surfaces and united at each end to the sub-adjacent surface; and means peripherally surrounding each of the last-said members and diametrically contractile to thereby effect inward longitudinal displacement of said extensions, whereby to clampingly constrict said transverse surfaces against the abutted members.

3. A jointure, comprising: a pair of abutted members; longitudinally spaced members extending transversely of the abutted members and resiliently integrated at their outer ends to adapt them to embrace radially extending portions of the abutted members; a longitudinally displaceable lateral extension, outwardly angled from the inner end of each of said transversely extending members; a member connecting the outer portion of said transverse members to the outer edge of each of said longitudinally displaceable extensions and united at each extremity to the sub-adjacent member to complete a truss; and means peripherally surrounding said trusses and contractile circumferentially of the device to effect inward displacement of said trusses sufficiently to clamp the abutted members together.

4. A jointure, comprising: a pair of abutted members; longitudinally spaced surfaces extending transversely of the device and resiliently integrated at their outer ends and adapted to embrace portions of the abutted members; a displaceable, outwardly angled, lateral extension of the inner end of each of said surfaces; a member connecting the outer portion of the united transverse members to each of said lateral extensions, said connecting members being adapted, upon release of the coupling, to constrain said displaceable extensions to move longitudinally and radially outwardly of the jointure and, upon actuation of the coupling, to move longitudinally of the jointure and radially inwardly; and means peripherally surrounding each of said connecting members and contractile circumferentially of the device to effect inward movement of said united connectors and lateral extensions, whereby to constitute the bend of each lateral extension a force-applying point abuttable against the abutted members to thereby effect clamping of said members.

5. A jointure, comprising: a pair of abutted members; a member congruent with at least a portion of the periphery of the joint and including transversely extending, longitudinally spaced members resiliently integrated at their outer ends and adapted to embrace the abutted members; a longitudinally movable lateral extension angled outwardly from the inner end of each of said transversely extending members; a member connecting the outer portion of each of the lateral extensions to the outer portion of said embracing formation and adapted with each of said lateral extensions to constitute a lever pivoted resiliently at said integration for transmitting forces to said abutted members; and means peripherally surrounding said connecting members and circumferentially contractile to actuate said connecting members and effect clamping of said abutted members; said contractile means being releasable to enable said connecting members to displace said extensions longitudinally away from the joint and radially outwardly into their initial angularity, thereby effecting unclamping of said abutted members.

6. A coupling for uniting abutted members,

comprising: a generally annular member symmetrical about its transverse axis and including a pair of substantially similar triangular portions spaced longitudinally of the abutment and resiliently united at their outer apices, to provide a radially extending, inwardly opening annular groove for embracing the abutting members, the longitudinal inner sides of said triangles being angled outwardly to form bends thereat, and the outer side of each of said triangles being constituted by a member bridging the longitudinal space between the ends of said lateral extensions and constituting a truss-side for constraining said extensions to move radially and longitudinally inwardly upon deflection thereof; and a radial-pressure applying means peripherally surrounding each of said bridging members for deflecting the ends of said extensions radially inwardly, whereby to effect transformation of said radial deflection into longitudinal compressive forces applied at said bends to said abutted members.

7. A coupling device, comprising: a generally annular member adapted to peripherally surround abutted members and including a longitudinally spaced pair of triangular, trusses disposed laterally of the abutted members and resiliently connected at their outer apices; and means peripherally surrounding each of said trusses laterally of said connection and circumferentially contractile thereagainst sufficiently to urge said trusses clamping together about said connection as a pivot and against said abutting members.

8. A coupling device comprising: a member encircling a pair of face-wise engaging annular couplable members; said first member including a resilient bridge portion radially embracing the couplable members and relatively rigid annular side portions extending laterally away from the plane of said coupling device; and means peripherally surrounding said side portions and

constrictable to effect radial contraction of the outer edges of said side portions and cause said side portions to move longitudinally toward each other to tightly clamp said couplable members together.

9. A jointure comprising: a pair of face-wise engaging annular couplable members and a clamping device embracing said couplable members and so constructed and organized with said 10 annular members as to be capable of forcing them longitudinally into pressure-tight engagement, said device having a bridge portion radially embracing the couplable members; annular side portions extending laterally away from the 15 plane of said jointure, and constrictable means peripherally engaging the free ends of said side portions; said bridge portion being relatively flexible in the plane of said jointure to serve as a virtual annular pivot and said side portions being relatively rigid; whereby radial contraction of said free ends will move said side portions toward each other about said virtual annular pivot to exert longitudinal compressive forces on said couplable members.
